HEAT EXCHANGER FIN TUBE

Frederick T. Elder, Mountain Lakes, N. J., assignor
to American Locomotive Company, New York,
N. Y., a corporation of New York

Application February 17, 1944, Serial No. 522,702

2 Claims. (Cl. 138—38)

This invention relates to a heat exchanger fin-tube having internal discontinuous fins.

An object of the present invention is to provide a heat exchanger fin-tube having discontinuous internal fins, a considerable number of which, extending both transversely and longitudinally of the tubular member, are formed from a single sheet of metal bonded to the interior of the tubular member of the fin-tube.

Other and further objects of and advantages achieved by the present invention will be apparent from the following description of an approved embodiment thereof.

Referring to the drawing forming a part of this application, Figure 1 is a section on the line I—I of Fig. 2, showing the fin-tube of the present invention, parts being shown in full; Fig. 2 is a section on the line II—II of Fig. 1; Fig. 3 is a section on the line III—III of Fig. 1; Fig. 4 is a plan of a metal blank employed in forming the fins of the tube; and Fig. 5 is an isometric view of a portion of the fin-providing sheet metal structure ready for insertion into the tubular member.

A fin-tube embodying the present invention is shown in the drawing and is designated by the reference numeral 1. For convenience a short tube is shown, but it may, of course, be of any desired length. It includes a tubular member 2 in which is disposed a fin-providing hollow metal structure 3 securely bonded to the inner face of the tubular member 2 as by soldering or welding.

The structure 3 is shown formed of a single sheet of metal, perforated and bent in a suitable manner to provide longitudinal rows of discontinuous fins. The structure 3 is of cylindrical internally corrugated form. It is contemplated that in a tube of large diameter, the structure 3 might be made up of several pieces disposed side by side, or in a tube of great length the structure 3 might be made up of several pieces disposed end to end.

In forming the structure 3, a flat piece of sheet metal 4 is chosen of suitable length and width for the tubular member with which it is to be employed. A plurality of longitudinal rows of elongated perforations 5 are formed in the sheet. The longitudinal edges of the sheet shown in Fig. 4 are designated by the numeral 6 and the transverse edges by the numeral 7. The perforations shown are diamond-shaped, but may be shaped in other suitable forms if desired.

After the perforations are formed the sheet is bent or arched through the longitudinal center (dot-dash lines) of each of the rows of perforations 5 to an angle equal to the angle α shown in Fig. 3. The longitudinal portions of sheet 4 be-

tween the rows of perforations and adjacent the edges 6 are then curved to form of sheet 4 the aforesaid cylindrical corrugated structure, the outside diameter of which will be equal to the inside diameter of the tubular member 2 in which the structure is to be disposed. The perforations are elongated in a transverse direction and the defining edges of each perforation diverge from the ends of the major axis of the perforation to the ends of the minor axis thereof.

The curved portions between the rows of perforations of the structure 3 form three longitudinal base portions 8 in the middle of one of which there will be a seam formed by the meeting of the edges 6. The portions between the perforations of each row and outwardly beyond the end perforations of each row to edges 7 form a plurality of short double-walled fins 9. Each fin 9 has two side walls 10, converging toward the axis of the tubular member, each of which provides a short strip-fin type fin surface. The side walls 10, at their edges opposite their apex, are integral with the adjacent base portions. As the perforations are diamond-shaped, each side wall 10 is keystone-shaped.

While three longitudinal rows of fins 9 have been shown in the drawing, it will be obvious that a greater or lesser number may be provided, if desired. The base portions 8 provide ample surface for bonding the structure 3 to the tubular member, insuring efficient heat transfer between the fins and the tubular member. Moreover, the structure 3 forms a simple, economical way of providing a tubular member with discontinuous internal fins. The advantage of discontinuous fins over continuous fins is well known. Suffice it to say that the discontinuous fins provide for a turbulent flow through the tubular member, the turbulence increasing the heat exchange rate.

While the perforations 5 are shown in the drawing also arranged in transverse rows, they may be staggered if desired.

While there has been hereinbefore described an approved embodiment of the invention, it will be understood that many and various changes and modifications in form, arrangement of parts and details of construction thereof, may be made without departing from the spirit of the invention and that all such changes and modifications as fall within the scope of the appended claims are contemplated as a part of this invention.

The invention claimed and desired to be secured by Letters Patent is:

1. A heat exchanger fin-tube comprising a tubular member; and a hollow sheet metal struc-

ture within said member having circumferentially alternate base portions and inwardly projecting V-shaped portions extending longitudinally of said member, said base portions engaging and being bonded to the inner face of said member and each of said V-shaped portions having a longitudinal row of spaced orifices, each of said orifices extending from one of the adjacent base portions through the apex of its V-shaped portion to the other adjacent base portion, said orifices providing of each of said V-shaped portions a longitudinal row of V-shaped double-walled fins.

2. A heat exchanger fin-tube comprising a tubular member; and a hollow sheet metal structure within said member having circumferentially

5 alternate base portions and inwardly projecting V-shaped portions extending longitudinally of said member, said base portions engaging and being bonded to the inner face of said member, and each of said V-shaped portions having a longitudinal row of spaced diamond-shaped orifices, each of said orifices having its major axis extending from one of the adjacent base portions through the apex of its V-shaped portion to the other adjacent base portion, said orifices providing of each of said V-shaped portions a longitudinal row of V-shaped double-walled fins, each wall of each of said fins being keystone-shaped.
